Atty's.

UNITED STATES PATENT OFFICE.

OSCAR LINDER, OF CHICAGO, ILLINOIS, ASSIGNOR TO IDEAL ROLLER & MFG. CO., OF CHICAGO, ILLINOIS, A CORPORATION OF ILLINOIS.

ROLLER.

Application filed July 9, 1921. Serial No. 483,409.

To all whom it may concern:

Be it known that I, OSCAR LINDER, a citizen of the United States, residing at Chicago, in the county of Cook and State of Illinois, have invented new and useful Improvements in Rollers, of which the following is a full, clear, concise, and exact description, reference being had to the accompanying drawing, forming a part of this specification.

This invention relates to an improved roller, and more particularly a printer's roller or lithographer's roller. The invention comprises an improved combination roller and washer, the washer being applicable, however, to any kind of roller or cylinder which consists of a rigid core that is covered with an elastic and resilient material.

One of the objections to rollers of the type having a rigid core covered with an elastic and resilient material is the ease with which the elastic composition can be damaged accidentally at the ends of the roller. A further objection is the tendency of the elastic composition to work loose from the rigid core at and near the ends of the roller upon slight accidental damage to the roller material at said ends. It is one of the objects of this invention to construct a roller which is provided with means whereby these and other objections readily apparent from the following description are substantially eliminated.

In the preferred construction of a roller, according to the teachings of this invention, a rigid washer preferably constructed of metal, such as steel, brass, fibre, hard rubber or any other suitable substance is attached to the end of the roller. The washer is preferably, but not necessarily fastened to the rigid core or stock of the roller by means of suitable screws, such as hereinafter described and illustrated in the accompanying drawings. This washer serves to protect the ends of the resilient roller material from accidental injury. The washers are preferably so secured to the roller that they form practically an integral part thereof, and whereby they will not be readily loosened or detached. However, they are so secured that if desired they can be removed, if it becomes necessary to recast the roller. The washers are preferably made of such a diameter that the outside periphery thereof does

not extend to the outer periphery of the resilient roller material.

The invention is illustrated in the accompanying drawings, in which—

Figure 1 shows the general construction of a typical roller partly in section with washer attached;

Fig. 2 is an end elevation of the roller shown in Fig. 1;

Fig. 3 is a view in elevation partly in section of a roller fitted with a split or slit washer;

Fig. 4 is an end view of the roller shown in Fig. 3;

Fig. 5 is an illustration in sectional elevation of a roller in which the washer is both screwed and cemented to the roller core and the roller material;

Fig. 6 is an end elevation of the roller illustrated in Fig. 5;

Fig. 7 illustrates another form of split washer;

Figs. 8 and 9 are views in sectional elevation of rollers which have rounded shoulders and illustrates the method of fastening the washers to this character of roller;

Fig. 10 illustrates a roller in sectional elevation having a plain core without shoulders; and,

Fig. 11 is an illustration in sectional elevation illustrating the use of the washer on a dampening or water roller used in lithography.

As illustrated in all of the drawings the washers are constructed so that their outer diameter is slightly less than the outer diameter of the resilient roller material. In the preferred form of roller the outside diameter of the washer is made from $\frac{1}{2}$ " to $\frac{1}{4}$ " smaller than the outside diameter of the resilient roller material. When a roller is fitted with a washer, as illustrated in the drawings, the elastic material of the roller may be made of either glue composition, vulcanized oil, rubber, fabric, leather, or any of the other materials frequently used, and this material may be compressed, as frequently happens in the commercial use of the roller, without any danger of having the washer bear on the surface or on the type which is being inked or moistened. Obviously, it would be undesirable and detrimental to make the washer so large so that in a practical operation of the roller there

would be a possibility of it bearing directly on any plate form or type which is intended to be touched only by the resilient roller material.

5 As illustrated in the drawings, the rigid roller core consists usually of a central body 16 and of spindles 17. The central body 16 is ordinarily of larger diameter than the spindles 17, as illustrated for example in 10 Figs. 1 and 8, thus forming a shoulder 18, which may be either square, as illustrated in Fig. 1, or round, as illustrated in Fig. 8. The washer 19 may be either fastened to the rigid core by means of screws such as 20, 15 or by any other suitable means. The washer, in some cases, may be fastened to the rigid core and the resilient material by means of a cement made from the same material from which the roller itself is made. 20 Both means may be used to fasten the washer to the roller, if desired. Thus for example, in a roller made of vulcanized oil, the washer may be cemented to the roller and to the rigid core by means of an elastic 25 cement 21 of vulcanized oil, as clearly illustrated in Fig. 5. This cement consists preferably, but not necessarily, of the same material, consistency and resiliency as the roller material. The thickness of this layer 30 of cement is preferably made from $\frac{1}{4}$ " to $\frac{1}{2}$ ".

The central core 16 may be of any desired material such as metal, wood, etc., and may be either solid, as illustrated in Fig. 1, or hollow, as illustrated in Fig. 8.

35 The resilient material 22 with which the roller is covered may be any one of the compositions or materials well known for this purpose in the art, as for example, vulcanized oil, rubber, glue composition and the like.

The washer 19 is preferably made of brass, but may be made of any other material, as for example, wood, fibre, or any material having the required rigidity. The washer should be made of a thickness which will conform to the requirements of the different kinds of rollers and the use to which the rollers are to be put. For example, in a roller such as illustrated in Fig. 1, in which there is a shoulder which supports the washer, a washer of about $\frac{1}{8}$ " thickness is preferably used; whereas, in a roller such as illustrated in Figs. 8, 9 and 10, a washer of from $\frac{1}{4}$ " to $\frac{1}{2}$ " thickness is preferably 55 used.

If the washer 19 is secured to the roller entirely by cement, a plain washer, similar to the one shown in Fig. 6, is used without the perforations shown in this washer. 60 However, the washer, which is secured to the roller core 16, is preferably provided with perforations which are countersunk to receive the flat-headed screws as illustrated in the drawings. The screws such as 20 65 are utilized to fasten the washer rigidly to

the roller core 16, these screws being machine screws, when the core is constructed of metal, the core being drilled and tapped to receive these screws. When the core is made of a softer material, such as wood, 70 obviously wood screws are used. Ordinarily it is advisable, in order that the washers 19 may be securely held to the core 16, to cement said washers to the core 16 and to the resilient material 22, as hereinbefore described, and to use in addition the screws holding the washers in position.

In practice spindles 17 are sometimes used which carry an enlargement such as 25. With spindles of this character slit or split 80 washers, such as illustrated in Fig. 4, are used. These slit or split washers can be pried apart at the ends after which the washer can be forced over the enlarged portion 25, and when thus fitted on the spindle 85 17, past the enlarged portion 25, the split ends of the washer can be forced together again and the split washer can then be secured to the core in any of the manners illustrated in the drawings and hereinbefore 90 described. Instead of using a split washer, as illustrated in Fig. 4, a two-piece washer, as illustrated in Fig. 7, may be utilized, this washer being fitted on the spindle 17 by assembling and fastening the two halves 26 95 and 27 of the washer over the spindle. When the washer is assembled on the spindle, as illustrated in Fig. 7, it can be secured to the core 16 in any one of the methods hereinbefore described.

In order to give the extreme end of the roller material the same resilience as that of the rest of the roller, it is preferred to bevel the roller material as shown at 28 in Figs. 1, 3 and 8. This beveling of the extreme end of the roller eliminates the restraining influence of the washer which would occur in case this bevel was not utilized.

In the construction of the washers, as 110 used in these rollers, the size of the center hole of the washer which fits over the spindle is immaterial. This hole may be made so that the washer will fit snugly on the spindle 17, or the center hole may be made 115 considerably larger. The outer diameter of the washer is the important consideration. This outer diameter of said washer must be made slightly smaller than the outer diameter of the outer resilient elastic material, 120 as hereinbefore described, and as illustrated in the drawings.

The washer may be also used with resilient rollers adapted to dampen the form or stone in lithograph presses and generally for all dampening rollers, lithograph and offset work. It is customary to cover such dampening rollers with one or more layers of water absorbing fabric such as wood, flannel, molleton, moleskin and the like, as 130

illustrated in Fig. 11. When the rollers are thus covered with this material, it is necessary to stretch the fabric very tightly over the roller. In the past rollers of this kind 5 have been made by stretching this material directly over the roller metal stock, but in recent commercial practice the core is first covered with a layer of some resilient elastic material such as vulcanized oil or rubber 10 before the water absorbing fabric is stretched over the roller. The object of this elastic material is to provide an elastic base under the fabric which gives more life to the roller. The main objections to using 15 such a resilient material under the water absorbing fabric resides in the ease with which said resilient material is damaged at and near the ends owing to the stretching of the fabric over said material. Most materials of high resiliency and elasticity are 20 mechanically weak and are consequently readily damaged when subjected to rough treatment. These resilient materials are very readily damaged when the fabric is 25 stretched over the roller, particularly since the fabric used for such dampening rollers must be stretched and sewed very tightly over the roller and tied tightly over the ends. 30 In the roller, as illustrated in Fig. 11, the washer 19 prevents injury to the end of the resilient elastic material because of the stretching of the water absorbing fabric such as 35 over said resilient material. It will be apparent from the drawings that the strains at the ends of the roller exerted by the water absorbing material 31 are taken up by the outer periphery of the washer 19. The invention herein illustrated and 40 described is particularly adapted for use with rollers constructed of vulcanized oil, as for example, the roller disclosed and illustrated in the Wolever Patents Nos. 1,161,756 and 1,283,392, but the invention is not limited to 45 use with this particular kind of roller, but can be used and applied to rollers generally

and particularly printers' and lithographers' rollers.

Obviously, the invention is not limited to any particular form or any particular use, 50 but the spirit of the invention is capable of many applications and many forms as set out in the appended claims.

Having thus described my invention, what I claim as new and desire to secure by 55 Letters Patent of the United States is:

1. In combination, a rigid roller core, a resilient roller material, rigid washers secured to the roller core and cemented to said roller material for protecting the ends of 60 said material.

2. In combination, a rigid roller core, a resilient roller material, rigid washers secured to the roller core for the protection of the resilient material, and a substantial layer 65 of elastic cement interposed between the washers and the resilient material and adapted to secure the washers to said resilient material.

3. In combination, a rigid roller core, 70 resilient roller material superposed upon said roller core; rigid washers secured to the roller core for the protection of said resilient material, and a substantial layer of resilient material similar to the material of 75 which the resilient roller material is made adapted to secure the washers to each end of said resilient roller material.

4. In combination, a roller core and a resilient roller material superposed upon said 80 core, rigid washers secured to the end of said roller core to protect said resilient material, and a substantial layer of elastic cement interposed between the washers and the roller and adapted to secure the washers 85 to the roller and the said resilient material, said washers having a diameter smaller than the diameter of the resilient roller material.

In witness whereof, I have hereunto subscribed my name.

OSCAR LINDER.
